UNITED STATES PATENT OFFICE.

FRANK PAUL ANDERSON, OF COLUMBUS, OHIO, ASSIGNOR OF ONE-HALF TO GEORGE C. URLIN, OF COLUMBUS, OHIO.

METAL CASEMENT WINDOW AND METAL WEATHER STRIP THEREFOR.

Application filed August 6, 1920. Serial No. 401,693.

To all whom it may concern:

Be it known that I, FRANK P. ANDERSON, a subject of the King of Denmark, and a resident of Columbus, in the county of 5 Franklin and State of Ohio, have invented certain new and useful Improvements in Metal Casement Windows and Metal Weather Strips Therefor, of which the following is a specification.

10 The object of my invention is to provide an absolutely dust and weather proof joint between a metal window casement and window frame, and also between the respective cooperating frames of the window.

15 My invention consists in the parts and in the construction, combination and arrangement of parts, as herein set forth and claimed.

In the drawings:

20 Fig. 1 is a perspective view of the window having my invention applied thereto, the sash being shown in partly open position;

Fig. 2 is a perspective view partly in section illustrating portions of adjacent hinged 25 sashes, and a casement in which they are mounted, showing my novel weather strip and the position it assumes when the sashes are in closed position;

Fig. 3 is a side elevation partly in section showing the weather strip between the lower portion of one sash and the upper portion of an adjacent sash in closed position;

Fig. 4 is a similar view showing the sash 35 in partly open position; and

Fig. 5 is a section on the line 5—5 of Fig. 2.

In the embodiment of my invention as illustrated and which shows a preferred 40 construction, the top and sides of each sash frame and the bottom of the casement is formed in the shape of a T-bar 10, while the top and sides of the metal casement and the bottom of each sash is formed in the shape 45 of a Z-bar 11. The Z-bar and T-bar are spaced apart from each other at 12 to provide for the reception of the cooperating members of the metallic weather strip which consists of a tongue 13 of spring metal, spot 50 welded or otherwise secured to the Z-bar, and curved outwardly therefrom and having a curved projecting edge 14, leaving a space 15 between said tongue and Z-bar.

A channeled strip 16 having a lip 17 is 55 spot welded or otherwise secured to the

T-bar. In the construction shown, the frames are attached to the casement by suitable hinges 18, and are provided with a pivoted bar 19 connecting the respective sash, whereby they are adapted to be moved 60 in unison in opening and closing. When the sash are in closed position the lip 17 will enter space 15 and bear against the spring tongue 13, while the tongue 13 will extend into the channel 20 to form a close 65 tight joint between the parts. The tongue 13 is curved outwardly at its edge from the Z-bar in order to permit of ready entrance of the lip within space 15. The inter-engagement of the lip in space 15 and the 70 tongue in channel 20, together with the close fit of the T-bar at each end with the cooperating Z-bar with the air space therebetween which serves as a non-conductor, provides a thoroughly efficient dust, dirt and 75 weather-proof construction. The parts are so constructed and arranged as to engage and disengage with the greatest ease and there is just sufficient spring in the tongue to permit this and at the same time provide for any possible inequalities or variations 80 in the parts, so as to effect a close non-binding fit.

While I have shown this construction of weather strip applied to cooperating sashes 85 hinged to the casement, I do not confine myself to this particular type of sash, but the same may be used regardless of the manner of attaching or mounting the sash.

It will be seen that with this construction a tight weather-strip joint may be formed entirely around between the window sash and casement, and between the respective sashes.

The cooperating spring tongue and lip 95 provide for such contraction and expansion of the metal as may take place. I prefer to construct the strip of zinc, spring bronze, brass or any equivalent rust-proof material to prevent corroding. As is well known 100 cold contracts and heat expands metal. My invention provides a flexible construction and allows the window to be tight in the coldest as well as in the hottest weather—regulated by the law of contraction and expansion, thus insuring an absolutely tight casement window under any and all conditions.

The parts, as illustrated and above described, are so constructed that they fit to 110

gether snugly without jamming or locking the window, and at the same time resulting in easy operation in opening and closing. Upon examination it is seen that there 5 is a two-point contact between the Z-bar and T-bar with a non-conducting air space therebetween in which the lip enters the space and the tongue enters the channel in cooperating contact with each other, so 10 that in order for any foreign matter to pass through from the outside to the inside of the window would require a circuitous route extending in six different directions. The extending edge of the Z-bar exposed 15 to the weather would effectually shield the entrance of any rain from entering space 12, and if it should by any possibility enter said space it would have to pass first forwardly, then backwardly and then forwardly between the tongue and lip to get 20 through the joint.

While I have shown a tongue and lip of preferred construction, I do not desire to be limited to this precise construction, but 25 variations may be made in either or both within the scope of the attached claims.

Having described my invention and its manner of use, what I claim as new and desire to secure by Letters Patent is:

30 1. In a metal casement window, the combination of a metal Z-bar and a metal T-bar having a two-point contact with each other and having a space therebetween, a spring tongue secured to said Z-bar within said 35 space and said tongue having a space between it and the Z-bar and a lip secured to said T-bar in said space and having a channel therein, and said tongue being adapted to detachably enter said channel and said

lip being adapted to detachably enter said 40 space between said tongue and said Z-bar, substantially as set forth and for the purposes specified.

2. In metal weather strips for metal casement windows, the combination of a T-bar 45 having a lip spaced apart therefrom by a channel, and a Z-bar having a tongue attached thereto and separated therefrom by a space, said lip adapted to detachably engage said tongue and Z-bar in said space 50 and said tongue adapted to detachably engage said lip in said channel to form a tight joint.

3. In metal weather strips for metal casement windows, the combination of a metal 55 T-bar having a lip spaced apart therefrom by a channel formed therein, and a Z-bar having a spring tongue attached thereto and partly separated therefrom by a space, the edge of said lip being curved away from 60 said T-bar, said lip adapted to detachably enter said space and said spring tongue adapted to detachably enter said channel and bear against said lip to form a tight joint. 65

4. In weather strips, a metal casement comprising top and side Z-bars and a bottom T-bar, sashes pivotally mounted therein and each comprising top and side T-bars and a bottom Z-bar, said Z-bars and T-bars 70 having a two-point contact, tongues secured to said Z-bars and channeled lips secured to said T-bar, whereby said tongue is adapted to enter said channel and said lip is adapted to fit between said tongue and said 75 Z-bar, and means for opening and closing said sashes in unison.

FRANK PAUL ANDERSON.
